[57] CLAIM

The ornamental design for a wall-mountable business card holder, as shown and described.

DESCRIPTION

FIG. 1 is a front perspective view of a wall-mountable business card holder showing my new design;

FIG. 2 is a top plan view;

FIG. 3 is a left side elevational view, the right side being a mirror image thereof;

FIG. 4 is a rear elevational view;

FIG. 5 is a bottom plan view;

FIG. 6 is a fragmentary cross-sectional view taken in the direction of arrows 6—6 in FIG. 1; and,

FIG. 7 is a fragmentary rear perspective view thereof with the backboard portion shown partially broken away for convenience of illustration.

FIG. 2.

FIG. 4.

FIG. 3.

FIG. 5.
